UNITED STATES PATENT OFFICE.

ALBERT M. WILSON, OF PHILADELPHIA, PENNSYLVANIA, ASSIGNOR OF
ONE-HALF TO BARTON L. BROWN, OF PHILADELPHIA, PENNSYLVANIA.

DESIGN FOR A NAME AND NUMBER PLATE.

No. 38,201.

Specification for Design.

Patented Aug. 28, 1906.

Application filed May 21, 1906. Serial No. 318,101. Term of patent 7 years.

To all whom it may concern:

Be it known that I, ALBERT M. WILSON, a citizen of the United States, residing at Philadelphia, in the county of Philadelphia and State of Pennsylvania, have invented a new, original, and ornamental Design for a Name and Number Plate for Telephone-Transmitters, of which the following is a specification, reference being had to the accompanying drawing, forming part thereof.

The figure is a front elevation of a name

and number plate for telephone-transmitters, showing my new design.

I claim—

The ornamental design for a name and number plate for telephone-transmitters as shown.

ALBERT M. WILSON.
